AUTOMATIC GRINDING MACHINE

Arthur J. Lewis, Stratford, Conn., assignor to:
 The Baird Machine Company, Bridgeport,
 Conn., a corporation of Connecticut

Application December 6, 1932, Serial No. 645,913

42 Claims. (Cl. 51—53)

This invention relates to grinding machines, and has particular reference to multiple spindle grinding machines in which a plurality of grinding tools operate simultaneously upon a corresponding number of pieces of work.

In the machine of the invention, the pieces of work are secured in proper position in a plurality of work holders arranged in circular series in a turret, which indexes after each tooling operation relatively to a tool carriage having a circular series of grinding tools which act successively upon each piece of work, each tool performing part of a single machining operation upon each piece of work. This arrangement permits all of

the tooling steps which are necessary to complete the grinding of each piece of work to be performed in a single machine, so that the work emerges in finished form without requiring further grinding.

20 The tool holders on the tool carriage are substantially axially aligned with the work holders when the turret is stationary, and are traversed relatively to the turret and the tool carriage to engage the tools with the work for the tooling operation and then return to inoperative position in readiness for the next tooling operation on successive pieces of work presented by the indexing action of the turret.

The tool carriage is reciprocated axially relatively to the turret to advance and retract the tools to and from the plane of the work in which the tooling operation takes place. These reciprocating movements of the tool carriage alternate with the traversing movements of the tool holders, so that the tools describe a rectangular path between their periodic tooling operations.

Superimposed upon this major reciprocating movement of the tool carriage, during the period that the tools are acting upon the work, is a rapid reciprocating movement of small amplitude, so that each tool, as it grinds, wipes across the surface of the corresponding piece of work to cause the minute scoring marks made by the tool to overlap and a smooth surface finish results.

45 As the tool carriage is retracted axially of the turret and the tools are withdrawn in line with the surfaces of the corresponding pieces of work just ground by the tools, the latter are simultaneously engaged and dressed by individually adjustable dressing tools arranged in circular series, which true and restore the surfaces of the grinding tools according to the nature thereof preparatory to the next grinding action. The reduction in radius of each tool resulting from the wear and dress thereof is compensated for by the tool hold-

er traversing mechanism, which superimposes upon the major traversing movement of the tool holders a small advancing movement equal to the amount which the radius of each individual tool was reduced, so that the tools perform a uniform grinding operation in each successive piece of work. A safety device is associated with this compensating mechanism which automatically disables it when one or more of the tools is worn and dressed down to the core or to the point where it is no longer effective or would injure the work, so that the tool does not materially engage the work during the following working cycle, if the operator neglects to replace it.

The tools are rotated continuously and the work holders are also rotated continuously in a direction opposite to that of the tools, except during the interval that the work holders are positioned at the loading station after having been advanced one by one to that point by the indexing movements of the turret. At the loading station the rotation of the work holders is automatically suspended to enable the operator to remove the finished pieces of work and replace them with new work. If the operator fails to remove finished work from the work holders which are advanced to the loading station, the entire machine is automatically stopped to prevent regrinding of the finished work.

The progressive grinding of the work with the machine of the invention permits the use of a series of different tools, each particularly adapted for performing a special step in the complete grinding operation. For example, the first tool of the series may be a roughing tool for dressing down the uneven surface of a casting, forging, or the like, to prepare it for the less coarse roughing cut of the succeeding tool, and so on to the final tool of the series, which may produce a fine polish or a lap, depending upon requirements. In addition to the initial selection of the various tools for producing the several ground effects, the tools are individually adjustable to produce deep or shallow cuts, the coarse or roughing tools being adjustable to produce a deep cut and the fine grinding tools a finer cut, although each tool invariably follows the fixed square motion path, modified by the rapid oscillation of the tool across the surface of the work and by the adjustment of the tool relatively to the work to compensate for the wear and dress of the tool.

This invariable relationship between the tools and the work is maintained for all positions of the machine, since all movements of its parts are

positive. Accordingly, the tools and work may be separated at will by retracting the tool carriage by means provided for that purpose to enable the operator to replace worn tools, or the like, at any stage of the operation, without disturbing the adjustment or relation of any part, so that the tool carriage may be restored to its initial position for resuming the tooling operation at the point where it was interrupted.

10 While the machine of this invention is particularly adapted for performing grinding operations, its use is not limited to that purpose, since the principles of operation and the timed movements thereof may be incorporated in a machine 15 for performing tooling operations of a different nature. These general principles of operation and timed movements are more completely described in the following description of the preferred embodiment of the invention which is illustrated in the accompanying drawings, in which

20 Figure 1 is a vertical section through the center of the machine, as seen along the line 1—1 of Fig. 3;

25 Figure 2 is a front elevation of the machine illustrating, in section, portions of the tool-holder traversing mechanism;

30 Figure 3 is a plan view of the machine;

35 Figure 4 is a horizontal section through the base of the machine, as seen along line 4—4 of Fig. 1, and illustrates the machine driving and turret indexing mechanism;

40 Figure 4A illustrates a substitute turret indexing cam for rendering the machine double-indexing;

45 Figure 5 is a vertical section through the gear box of the driving mechanism, as seen along line 5—5 of Fig. 4;

50 Figure 6 is a vertical section through the driving mechanism, as seen along the line 6—6 of Fig. 4 and particularly illustrates the arrangement of the two-speed shaft thereof;

55 Figure 7 is an enlarged axial section through the work-holding chuck;

60 Figure 8 is an enlarged axial section through the work-holding chuck driving mechanism;

65 Figure 9 is a development of the tool carriage reciprocating cam;

70 Figure 10 is a horizontal section through the machine as seen along the line 10—10 of Fig. 1, and illustrates the arrangement of the tool dressing devices;

75 Figure 11 is an enlarged section of one of the tool dressing devices;

80 Figure 12 is a horizontal section through the tool carriage, as seen along the line 12—12 of Fig. 1, and illustrates the arrangement of the tool holders;

85 Figure 13 is an enlarged partial section through the tool carriage and illustrates the structure and arrangement of the tool holders and their operating cams;

90 Figure 14 is a diagram illustrating the rectangular or square motion path of the tools;

95 Figure 15 is a top view of a piece of work and the tool cooperating therewith;

100 Figure 16 is a horizontal section through the base of the machine as seen along line 16—16 of Fig. 1 and illustrates the safety stop and work release mechanisms;

105 Figure 17 is an enlarged top view of the tool holder traversing and tool wear and dress compensating mechanisms;

110 Figure 18 is a front view thereof;

115 Figure 19 is a vertical section through the auto-

matic stop device of the compensating mechanism, as seen along the line 19—19 of Fig. 17;

120 Figure 20 is a partial side view of the base of the machine showing the work release treadle at the loading station;

125 Figure 21 is an enlarged view of the safety mechanism which stops the machine if the operator fails to operate the treadle to remove finished work; and

130 Figure 22 is a partial section through the manual tool carriage elevating mechanism, as seen along line 22—22 of Fig. 12.

135 Referring to Fig. 1 of these drawings, numeral 20 designates the base of the machine upon which is supported the column 21 having the 15 lateral extension 21' and which carries the pedestal 22, which serves as the axis of the machine.

The driving mechanism

140 Suitably supported on a bracket 23 mounted on the base 20 of the machine is the driving motor 24, which drives through belts 25 the pulley 26 keyed on the end of a horizontal drive shaft 28 journalled in a gear box 27 secured to the base 20.

145 As illustrated in Figs. 4 and 5, a skew gear 29 is keyed on drive shaft 28, and a spur gear 30 is journalled thereon. This spur gear 30 is provided with an extension which houses a disc clutch 31, the other element of which is connected to clutch release collar 22 splined on shaft 28 and 30 operable by a yoke 33 connected to shifter rod 34 slidably mounted in the gear box 27.

150 Spur gear 30 meshes with spur gear 35 journalled on jack shaft 36 journalled in the gear box 27 (Fig. 4). The spur gear 35 is provided with 35 an extension housing normally engaged disc clutch 37, the other element of which is connected to release collar 38 splined on jack shaft 36 and operable by a yoke 39 mounted on shifter rod 40 slidable in gear box 27 and shiftable by a rod 41 40 having a crank 42 at one end engaging a collar 43 on rod 40 and actuatable in a manner to be described.

155 The skew gear 29 on drive shaft 28 meshes with a skew gear 44 on cross shaft 45 journalled 45 in gear box 27 and this cross shaft drives a second parallel cross shaft 46 by means of spur gears 47 and 48. Cross shaft 46 is suitably journalled in gear box 27 and carries a worm 49 which meshes with worm wheel 50 journalled on jack shaft 36. 50 This worm wheel 50 is provided with a plurality of spring pressed pawls 51 engaging a ratchet 52 formed integrally with spur gear 35 and driving the latter in a clockwise direction independently of meshing spur gear 30 when clutch 31 is disengaged.

160 It will be seen that when clutch 37 is engaged, as is the case when the machine is operating normally, jack shaft 36 is driven at a certain speed directly by motor 24 through belt 25, pulley 26, 60 drive shaft 28, skew gears 29 and 44, cross-shaft 45, spur gears 47 and 48, cross-shaft 46, worm 49, worm wheel 50, pawls 51, ratchet 52, clutch 37, and collar 38 which is splined on jack shaft 36.

165 It will also be seen that when clutch 31 is engaged, spur gears 30 and 35 are directly driven and that, because of the higher gear ratio, the ratchet 52 is driven faster than the pawl worm wheel 50 and accordingly creeps so that jack shaft 36 is driven faster than is the case when clutch 31 is disengaged. This drive mechanism accordingly provides high and low speeds for shaft 36, depending upon the condition of clutch 31.

170 Jack shaft 36 is provided with a worm 53 which meshes with worm wheel 54 keyed on vertical cam 75

shaft 55 journaled at its lower end in a step bearing 56 in the base 20, and near its center and upper end in the bearings 57 in the base 20 and frame 21, respectively. This shaft carries a cam disc 58 having several cams, one of which, inside ring cam 58', cooperates periodically with one end of bell crank 60, which is pivoted on the gear box 27 and engages a collar 61 on the shifter rod 34 of normally disengaged clutch 31. When cam 59' 5 engages crank 60, the latter shifts rod 34 to the left, as seen in Fig. 4, to engage clutch 31 so that cross-shaft 36 and consequently cam shaft 55 are driven at a higher speed, ratchet 52 slipping past its pawls 51 in the manner described. Clutch 31 10 remains engaged until cam 59 engages bell crank 60 to shift rod 34 to the right to disengage clutch 31 so that cam shaft 55 is driven at slower speed 15 through pawls 51 and ratchet 52.

The turret

Journalled on bushings 63 on the pedestal 22 of the machine is the turret 64, which is rotatably supported on a track 65 mounted on the upper surface of base 20. The turret 64 is indexed 20 rapidly during the high speed drive period of the cam shaft 55, and the indexing mechanism includes a pair of spaced roller pawls 66 mounted on cam ring 58 and successively engaging one of the spaced lugs 67 on ring 68 secured on the lower 25 edge of the turret 64. Each indexing movement rapidly rotates the turret one step through a predetermined angle between adjacent tooling stations in a manner readily understood.

The turret 64 is locked against movement during the period between its indexing movements by a pin 69 adapted to engage any one of a plurality of notches or slots 70 in the turret 64. This pin is slidably mounted in the base 20, is held in place by cap 71 and is normally urged inwardly 30 into one of the notches 70 by spring 72. The pin 69 is provided with a side slot into which projects the end of a bell crank 73 pivoted on the base 20 and engaging a cam 74 on cam disc 58. This cam 74 actuates lever 73 to withdraw pin 69 from the corresponding notch 70 at the beginning of the indexing movement of the turret 64, holds pin 69 35 disengaged during the indexing movement of the turret and then releases pin 69 for insertion in the next notch 70 after the indexing movement 40 is completed, so as to lock the turret while the grinding operations take place.

In addition to the locking pin 69, the turret 64 is provided with a friction brake at the finishing stations on the left hand side of the machine, as seen in Figure 4. This brake comprises a spring shoe 64' engaging the exterior surface of the turret 64 and adjustable to vary its frictional resistance by means of a set screw 65' mounted on the base 20 (Figures 1 and 4). The brake 45 holds the turret 64 firmly against the pedestal 22 so that any looseness is taken up at the finishing stations whereby there can be no variation in the grinding action and absolute accuracy at the finishing stations is secured. The brake also prevents any tendency of the turret to over-run 50 during the indexing movements thereof.

The machine may be readily converted from single indexing, i. e., where each tool cooperates with each successive piece of work, to double indexing, where the tools skip alternate pieces of work. In other words, instead of moving through the angle between two adjacent tooling stations, the turret moves through a double angle. This conversion is accomplished by substituting for 55 the two-roller cam disc 58 the four-roller cam

disc 58' illustrated in Figure 4A, which carries the four rollers 68' arranged to engage two successive lugs 67 on ring 68 instead of one lug 67, so that the turret is moved through a double angle, skipping alternate stations. The purpose 5 of this double indexing will be explained later. In order to provide for the locking of the turret between the double indexing movements thereof, the cam 74' for controlling locking pin 69 is made twice as long as cam 74, so that the pin is held 10 retracted and only engages alternate notches 70 in the turret 64.

The work holders

The turret 64 carries the chucks or other work 15 holders, of which there may be any number consistent with requirements and the size of the machine. In the machine illustrated eight chucks are employed. The construction, size, and shape of the chucks depend upon the work to be held 20 therein. By way of illustration, the work W illustrated in the drawings is an automobile hub, the interior surface of which is to be ground. The chuck for holding such a hub is illustrated in enlarged section in Fig. 7 and comprises a 25 block 75 bolted on the upper end of a tubular sleeve 76 rotatably supported by upper and lower roller bearings 77 in an opening in the turret 64, as shown in Fig. 1. The joint between the block 75 and the turret 64 is sealed by ring 77' against 30 the water supplied to the grinding tool, which normally flows from the work W into block 75, through discharge slot 78 therein, and into the gutter 79 in the base 20, which discharges through pipe 80 at the rear of the machine, as shown in 35 Fig. 4. The block 75 is fitted with a cup 81 for receiving the work W, which has a flange provided with openings through which centering pins 82 of the cup pass.

Slidably mounted within the sleeve 76 and centered therein by bushing 83 is a spindle 84, which is normally urged downwardly by spring 85. The spindle 84 is provided with a head 86 having three pivoted pawls 87, forming with cup 81 a 40 collet chuck in which the work W is gripped. The upper ends of the pawls 87 are urged by the lower rim of cup 81 into a groove in the work and the opposite ends of the pawls 87 serve as detents 88, which, when the spindle 84 is raised, engage the lower rim of cup 81 and withdraw the pawls 50 87 from the groove in the work W to release it. Pawls 87 are normally urged within cup 81 and into engagement with the work W by the spindle spring 85.

Splined on the lower end of chuck sleeve 76 is 55 the male element 89 of a cone clutch, the female element 90 of which is journaled on sleeve 76 and has an integral spur gear 91, which meshes with a spur gear ring 92 journaled on ball bearings 93 on the pedestal 22 of the machine. The 60 lower edge of gear ring 92 is provided with a bevel gear 94, which meshes with and is constantly driven by bevel gear 95 on the end of shaft 96 journaled in the base 20 of the machine. The shaft 96 is driven directly by drive shaft 28 65 through bevel gears 97 and 98, as is illustrated in Fig. 4.

Spindle cone clutch 89-90 is normally held in engaged position by a coil spring 99 interposed between male clutch element 89 and a ring 100 70 mounted in the end of sleeve 76. The work-holding chucks and their spindles are accordingly driven continuously throughout the several grinding operations and are stopped only to enable the operator to remove the finished work W and 75

reload the chucks. The stopping of the chucks and spindles at the loading station is performed automatically by a cam-operated release mechanism for the spindle clutches. This mechanism includes a grooved collar 101 in the male clutch element 89, in the groove of which lie the ends of a forked release lever 102 which is pivoted between lugs 103 depending from the base of turret 64, as shown in Figs. 1 and 16. The free end 10 of the release lever 102 carries a roller 104 which, as the turret rotates, eventually engages fixed ring cam 105 mounted on the base 20 at the front or loading station of the machine. The cam 105 lifts lever 102 about its pivot 103 to dis- 15 engage the chuck-rotating clutch 89-90 and is of sufficient length to simultaneously accommodate two rollers 104, so that after each indexing movement of the turret 64, two chucks are sta- 20 tionary. During the next indexing movement of turret 64, one of the rollers 104 moves off of the cam 105 and the spring 99 reengages the clutch 89-90 to rotate the corresponding chuck and spindle.

25 Loading and unloading

During the interval that the two chucks remain stationary at the loading station, they are automatically opened for the release and removal of the finished work W and for reloading with the 30 next piece of work to be ground. The mechanism for opening the chucks includes a pair of vertical pins 106 which are aligned with the lower ends of the spindles 84 of the two chucks which remain stationary at the loading station between index- 35 ing movements of the turret 64. These pins 106 slide vertically through guide bar 107 mounted on the pedestal 22, and are adjustably threaded in arms 108 pivoted in the forks of cranks 109 secured to a shaft 110 journaled in a bracket 110' 40 on pedestal 22. The left-hand end of shaft 110, as seen in Figs. 1 and 16, carries the lever 111 having roller 112 at its end. This roller 112 engages inverted crown cam 113 keyed on cam shaft 55 and operative to rotate shaft 110 at the end of each 45 indexing operation so as to cause pins 106 to engage and lift the corresponding spindles 84 of the two stationary chucks located at the loading station at that time. Elevation of spindles 84 causes the detents 88 of the chuck pawls 87 to engage 50 the lower rim of chuck cap 81 and swing the ends of pawls 87 out of the groove in the work W to release the latter. The length of crown cam 113 is such that the two chucks at the loading station remain open during the interval between index- 55 ing movements of the turret 64 so the operator has ample time to remove the finished piece of work W from the open chucks and replace them with new pieces of work.

The chuck-controlling shaft 110 is also provided with vertical lever 114 having the roller 115 which engages the ring cam 116 on the under surface of worm gear 54 of cam shaft 55. This ring cam 116 succeeds crown cam 113 in operation and is complementary thereto and serves to positively 60 retract and hold retracted the spindle-engaging pins 106 during the indexing movements of the turret 64 so that there can be no interference between the pins 106 and the chuck spindles 84 when the turret 64 is moving.

70 During the dwell period of the turret 64 when the two chucks at the loading station are open, the work W may be readily removed from and placed in the chucks. Before the operator can have access to the finished work W presented at 75 the loading station he must withdraw fingers 117

which lie over the work but out of contact therewith, as shown in Figures 2, 10 and 20. These fingers 117 are mounted on a horizontal shaft 118 pivoted in lugs 119 on the apron 120, which is mounted on the base 20 and encloses the chucks, 5 work W, and other working parts of the machine. The left-hand end of shaft 118, as seen in Figures 2, 10 and 20, carries the lever 121, to the end of which is pivoted one end of rod 122 connected at its lower end to the treadle 123 pivoted on lugs 10 124 on the base 20 of the machine at the loading station. The fingers 117 are urged downwardly to a position over the work W by spring 125 and a pin 126 limits this downward movement of the fingers to hold them out of contact with the work. 15

The operator of the machine is supposed to remove each finished piece of work W from its chuck at the loading station and replace it with a new piece during the dwell period of the turret, and to enable him to do this he depresses treadle 20 123 to withdraw fingers 117 from the work W. A safety device (Figures 2, 16 and 21) is provided to stop the machine in the event that the operator fails to remove a finished piece of work. This safety device is operative only when the operator 25 fails to depress treadle 123 preparatory to removing the work. The safety device includes a link 127 connected at one end by a pin-and-slot 128 to treadle rod 122 and at the other end to a bell crank lever 129 which is fixed to shaft 130 jour- 30 naled through a boss 131 on the base 20. The inner end of shaft 130 carries a crank 132 which engages crown cam 134 mounted on the upper surface of worm wheel 54. Pivoted on link 127 near its center is a rocker plate 135 having two 35 lateral detents 136 and 137 which are adapted under certain conditions to respectively engage abutments 138 and 139 on plate 140 secured to the base 20. Pivoted on link 127 is a latch 141 having a notch forming a hook 142 at its extreme 40 end which cooperates with a pin 143' on the end of stop handle 143, which is fixed to the end of rod 41, which, it will be recalled, controls master clutch 37 of the drive mechanism of the machine. This clutch is normally engaged and, when disengaged by the rotation of rod 41, stops the machine. A disengage lever 144 is pivoted on link 127 and, when manually thrown to operative position, lifts latch 141 out of the path of the pin 143' to disable the safety device. 50

The safety device is so arranged that when the operator depresses treadle 123 to release the fingers 117 and remove the finished work from the two then open and stationary chucks, link 127 is depressed by treadle rod 122 to lower plate 135 55 and cause its lower detent 137 to engage abutment 139, while upper detent 136 passes below and clears abutment 138. This action causes plate 135 to rotate about its pivot so that detent 137 engages latch 141 to lift the hook 142 of the latter clear of pin 143' on stop handle 143. Immediately thereafter crown cam 134 actuates crank 129 to move link 127 to the right as seen in Figs. 2 and 21. Since hook 142 of latch 141 has been withdrawn from pin 143' of stop handle 60 143 by the depression of treadle 123, the hook 142 does not actuate the handle 143, and the feeler action of crown cam 134 is ineffective. However, if the operator has failed to depress treadle 123 preparatory to removing the finished work from 65 the stationary open chucks, link 127 remains in raised position and the feeler action of cam 134 moves link 127 to the right so that detent 136 engages abutment 138 to withdraw detent 137 from latch 141. Continued movement of the link 70 75

127 by the cam 134 causes latch hook 142 to pull pin 143 to the right to rotate rod 41 and disengage clutch 37 to stop the machine. The machine may be stopped manually at any time by movement of the handle to the left, as seen in Fig. 2.

The tool carriage

The pillar 145 of the machine upon which the tool carriage is mounted is secured upon pedestal 22 by bolts 146 and its upper end is seated in an opening in the column extension 21', which is covered by cap plate 147. This pillar 145 is provided with an axial bore 148 into which projects the upper end of push rod 149 which is slidably mounted in the pedestal 22. Extending crosswise through opposite elongated vertical slots 150' in the pillar 145 is a cross-bar 150. Threaded through this cross-bar and engaging the upper surface of push rod 149 is adjusting rod 151 which extends vertically through bore 148 of pillar 145 and projects through cap plate 147 in which it is rotatably guided. The projecting upper end of adjusting rod 151 is squared at 152 for receiving a handwheel or crank, not shown, by means of which rod 151 may be rotated to raise or lower cross-bar 150 for a purpose to be described.

The tool carriage 153 is splined upon pillar 145 by means of the four splines or keys 154, but these keys do not bear any lateral strains caused by the tendency of the entire carriage and pillar combination to rotate, because such lateral strains are absorbed by a lateral key 155, which slides vertically in guideways 156 in column 21. The carriage 153 is provided with lateral slots into which the ends of the cross-bar 150 fit, so that reciprocating vertical movement of the cross-bar raises and lowers the tool carriage 153. The tool carriage is reciprocated by the action of crown cam 157 mounted on the under side of worm wheel 54 and shaped as illustrated in development in Fig. 9. This cam 157 is engaged by a follower roller 158 mounted on the end of lever 159 pivoted at 160 on the pedestal 22. The opposite end of lever 159 engages the lower end of push rod 149, so that carriage 153 is raised and lowered in accordance with the configuration of cam 157, the lowermost track 161 of which is rippled to provide small rapid reciprocating movements of the tool carriage for a purpose to be described later.

Four rods 168 slidably extend downwardly from the upper flange of the column extension 21' through which they are adjustable lengthwise by nuts 169. Each of these rods is fitted with a collar 170, to which one end of tension spring 171 is connected. The other or lower end of each spring 171 is secured to a stud 172 secured in lower motor bracket 163. These springs counterbalance the greater portion of the weight of the heavy carriage 153 so that it may be moved readily by the cam 157 and manually by mechanism to be described.

The tool holders

The carriage 153 is provided with six pairs of upper and lower brackets 162 and 163, respectively, which are connected by vertical guards 164, and which are spaced equi-angularly with six of the eight chucks on the turret 64. This leaves a gap between two pairs of brackets corresponding to the two remaining chucks below. Mounted between each pair of upper and lower brackets 162 and 163, and protected by the guards 164 is an electric motor 165 connected electrically to

a source of power, not shown. The shaft 166 of each motor 165 extends downwardly through an opening in the corresponding lower bracket 163 and carries a grooved pulley 167, as shown in Figs. 1, 2 and 13.

Journalled in brackets 173 formed integrally with carriage 153 and located below the corresponding motors 165 and arranged eccentrically with respect to the shafts thereof are vertical pivot pins 174 on which are mounted the tool holders 175, as is illustrated in Fig. 13. These tool holders 175 each include upper and lower ears 176 which extend over the upper and lower ends of the corresponding bracket 173 and receive the corresponding ends of pivot pin 174. These ears 176 extend from the tool shaft housing 177, which is fitted with the elongated removable cap 178 and with a lateral web 179 covering the bracket 173. Journalled in suitable bearings in the shaft housing 177 of tool holder 175 is the tool shaft 180 which carries the grinding wheel 181 at its lower end and the grooved pulley 182 at its upper end. The pulleys 167 and 182 lie in the same horizontal plane and are connected by a plurality of belts 183, by means of which the corresponding motor 165 drives the grinding wheel 181.

The lower ear 176 of each tool holder 175 is provided with an integral lug 184 through which is threaded a set stud 185 locked in adjusted position by a lock nut 186. The tip of the stud 185 engages the outer end of actuating pin 187, whose inner end engages ring cam 188 encircling tool carriage 153 and bearing on a bushing 189, as shown in Figures 1 and 13. By means of the stud 185 the corresponding grinding wheel may be adjusted to cut initially deeply or shallowly, depending upon requirements. The ring cam 188 is made up of a plurality of separate segments of varying contour, supported loosely on ring gear 190 by the pin-and-slot arrangement shown in Figure 13, so that the segments bear on bushing 189 and the gear 190 serves only to rotate them on the bushing. The cam 188 and gear 190 are housed within an enclosure comprising an overhanging apron 191 on the carriage 153 and a ring 192 which is seated in a groove in the surface of the carriage and closes the space between the latter and the lower rim of apron 191. The actuating pins 187 are slidably mounted in bosses 193 formed on the outer surface of apron 191, and are urged into contact with the ring cam 188 by the pressure applied thereto by the tool holder springs 194, which are secured at one end to a pin 195 in the lugs 184 of the tool holders 175 and at their other ends to pins 196 on the cam apron 191.

The angular position of cam 188 determines the radial position of each of the grinding wheels 181, since movement of the cam 188 causes pins 187 to displace the corresponding tool carriers 175 about their pivots 174. The angular position of the cam 188 is adjusted by a pinion 197 mounted on the lower end of a vertical shaft 198 located within a shaft housing 199 mounted on the front of the machine at the operator's position or loading station. The reduced lower end 200 of the shaft 198 housing 199 is seated in a socket in the upper surface of the cam apron 191 and the upper end thereof is secured to the carriage 153 by screws or the like, passing through lugs 201 on the housing 199, as illustrated in Figure 2.

The lower end of shaft 198 is suitably journalled in the shaft housing 199 and the upper end thereof is journalled in a sleeve 202 which in turn is journalled in shaft housing 199. The upper end of sleeve 202 is mushroomed to form the 75

plate 203 which rests upon the upper end of shaft housing 199 and upon which is mounted by bolts 204 the lever 205, as is illustrated in Figures 2, 3, 17, and 18. The end of lever 205 over the plate 5 203 is hollow to form a housing 206 for worm wheel 207 keyed upon the upper end of shaft 198 and bearing upon a boss 208 on plate 203. A collar 209 secured in the end of the shaft 198 assists in locking the latter against endwise movement 10 and also secures worm wheel 207 thereto.

Journalled in housing 206 of lever 205 is a short shaft 210 having the worm 211 meshing with worm wheel 207 and a squared projecting end 212 for the reception of a crank, or the like. The 15 worm 211 and wheel 207 are inherently locked with respect to each other so that shaft 198 is rotated only when lever 205 is oscillated or when worm 211 is rotated.

The free end of lever 205 is provided with a 20 roller 213 which moves in a vertical groove or slot in relatively stationary block 214 as the carriage rises and falls in response to actuation by cam 157. The block 214 is secured to the end of a horizontal push-rod 215 which is slidably mounted in the 25 upper end of column 21 and is prevented from rotating by a lateral extension 216 which is guided on a rod 217 secured in the column 21. The lower surface of the extension 216 is fitted with a roller 218 which is seated in and follows the 30 groove of cam 219 mounted upon the upper end of cam shaft 55 and housed within the column 21. Cam 219 is so shaped that lever 205 is oscillated as cam shaft 55 rotates, and, inasmuch as vertical shaft 198 is locked to lever 205 because 35 of the worm and wheel combination 207, 211, the shaft 198 also oscillates. Because shaft 198 is connected to ring cam 188 through pinion 197 and ring gear 190, the cam 188 also oscillates to move actuating pins 187 outwardly and inwardly. 40 These movements of pins 187 cause tool holders 175 to oscillate about their pivots 174 so that their grinding wheels 181 are reciprocated in a horizontal plane. The several segments of the cam 188 may be of different shapes to provide corresponding 45 movement of their tools. In this way, coarse grinders may be given a greater throw than the fine grinders, and the like.

The cam 219 is so timed with respect to cam 50 157 that the respective movements of the two cams alternate, i. e., when cam 157 moves the carriage 153 upwardly to withdraw the grinding wheels 181 from the work W, cam 219 holds lever 205 relatively stationary, and when the following action of cam 219 takes place to move 55 the grinding wheels 181 laterally, cam 157 holds the carriage 153 stationary. Likewise, during the following downward movement of the carriage, which immediately follows the indexing of the turret 64, the lever 205 is stationary, and when 60 cam 219 then moves the lever 205 to bring the grinding wheels 181 into engagement with the work W, cam 157 holds the carriage stationary.

While the work is being ground, a small vertical reciprocation is imparted to the carriage 153, 65 and consequently the grinding tools 181, by the rippled track 161 of cam 157 to cause the grinding rings on the work to overlap and produce a smoother surface. This square motion of the grinding wheels 181, which is secured by cams 70 157 and 219, is illustrated diagrammatically in Fig. 14, and the relation of the grinding wheels 181 to the work W is illustrated in Figs. 1 and 15, the work W being rotated in a counter-clockwise direction and the grinding wheel 181 in a clock-

wise direction, as seen from above, although these movements may be reversed if desired.

The grinding wheels 181 and the work W are flushed with water or other fluid during the grinding operation by nozzles 220, each controlled by suitable valves 221, and connected by pipe fittings 222 to a manifold pipe 223 secured to inner surface of apron 120 and supplied by pipe 224 at the rear of the machine (Figs. 1 and 10).

The tool dressing devices

Mounted in the path of each grinding wheel 181 during its withdrawing movement, is a dressing tool 226, which trues and dresses the grinding wheel after each grinding operation. This tool is a diamond chip or equivalent dressing element and, as illustrated in Fig. 11, is mounted in a holder 227 threaded into an arm 228 pivotally mounted on a bracket 229 secured to the 20 apron 120 by a bolt 230. Arm 228 is locked in adjusted position on bracket 229 by pivot bolt 231 and the tool 226 may be more finely adjusted by screwing its holder 227 in or out of the arm 228. The head 232 for making this fine adjustment is graduated and cooperates with a pointer 233 fixed on the arm 228 which enables the operator to obtain fine, accurate adjustment for each of the dressing tools. A spring 234 holds the tool against loosening because of vibration, 30 or the like. Accordingly, as the six grinding wheels 181 rise from the work W after the grinding operation, the constantly rotating wheels 181 are trued and dressed by the corresponding dressing tools 226. Each tool is dressed according to 35 its requirement, although all tools are dressed simultaneously.

Inasmuch as each grinding operation and the subsequent dressing operation remove some of the surface of the grinding wheel, its diameter 40 gradually decreases and so it must be advanced a corresponding amount to compensate for the reduced diameter in order that the subsequent grinding operations of the tool will be effective and uniform. The mechanism for providing this 45 compensation for wear and dressing losses on the grinding wheels includes a ratchet wheel 235 secured on the outer end of the worm shaft 210. Pivoted on worm shaft 210 is a pawl carrier 236 which carries at its lower end the pawl 237 engaging ratchet 235 and fitted with a lug 238 which is engaged by the free end of leaf spring 239 mounted on carrier 236. The pawl 237 has a knob 240, by which the operator may disable the compensating mechanism by pulling pawl 50 from the ratchet 235, so that spring 239 snaps over lug 238 to hold the pawl 237 disengaged. A link 241 is pivoted upon the upper end of pawl carrier 236 and is pivoted at its opposite end to one arm 242 of bell crank 243 which in turn is 55 pivoted on the lever 205. The other, or free end 244 of bell crank lever 243 is adapted to engage abutment 245 during the backward movement of lever 205, and since the bell crank 243 is carried by the lever 205, this action will result in 60 oscillation of the bell crank 243. The resultant movement of link 241 to the right, as seen in Fig. 18, will cause pawl 237 to rotate ratchet 235, shaft 210, worm 211, worm wheel 207, shaft 198, pinion 197, ring gear 190 and cam 188 through a 65 small predetermined angle and since this rotation is superimposed upon the oscillating movement of cam 188, the result is a permanent advance of the corresponding grinding wheel a distance equal to the decrease in its radius caused by the wear 70 75

and dress thereof. This compensating adjustment is timed to take place during the upper horizontal course of the grinding wheel, as seen in Figure 14, so that the adjustment takes place when the grinding wheel 181 is withdrawn from the work W.

In order to restore the pawl 237 for the next operation, a tension spring 246 is connected between the bell crank 242 and the lever 205, which, when the lever 205 moves forward to advance the wheel 181 against the work, pulls link 241 to the left, as seen in Figure 18, to return pawl 237 to its starting point, the latter clicking over the teeth of ratchet 235 to assume its new position. A stop screw 247 for the bell crank 242 limits this restoring action of the spring 246 and is adjustable.

The compensating movement of each grinding wheel takes place during each square movement thereof and is continued until the grinding face of a wheel is worn and dressed down to a point where it is no longer effective. This condition of a wheel is definitely known to take place after a predetermined number of compensating movements of the mechanism and after that condition is reached it is desirable to stop further compensating movements so that the worn tool will not injure the work or other part. Since the number of compensating movements is known, and since the rotation of worm wheel 207 by worm 211 is proportional to these movements, the worm may be employed to determine the limit of these movements. To this end the worm 207 is fitted with a crown cam 248 which gradually approaches a detent 249 located in its path and slides vertically in an opening in the housing 206. This detent normally holds latch 250 retracted, this latch having a hook 251 which fits over the edge of an eye in detent 249 through which the latch 250 passes. A spring 252 urges the latch to the left, as seen in Figure 19. The latch 250 is slideable in a boss 253 in the housing 206 and its free end is notched for cooperation with the edge of pawl carrier 236 of the compensating mechanism when the latch is released. When the worm wheel 207 has rotated the aforementioned predetermined number of stops, detent 249 rides upon cam 248 to release the latch 250, which is thereupon urged to the left as seen in Figure 19, so that its end steps over the edge of link 241 upon its compensating stroke so that the end 244 of bell crank 243 remains retracted and will not be advanced by the subsequent stroke of the lever 205. Accordingly, the compensating mechanism is disabled automatically and will not again function until restored by the operator after he has replaced the worn grinding wheel with a new one. In order to restore the disabled compensating mechanism, the operator fits a crank or handwheel on the squared end 212 of worm shaft 210 and rotates the latter in a direction opposite to that in which it was moved by the pawl 237 until the mechanism is restored to its initial position. Then the operator disengages latch 250 from pawl carrier 236 and catches its hook end within the eye of detent 249 and the mechanism is ready for its next operation.

Manual tool carriage elevation

In order to more readily replace a worn grinding wheel or make other changes, and the like, the carriage may be raised manually and restored without changing its adjustment with respect to the work. The mechanism for raising

and lowering the carriage is located at the front of the machine on shaft housing 199. It is enclosed in a casing 254 formed integrally with the shaft housing 199, as is illustrated in Figs. 2, 12 and 22. Extending through casing 254 and keyed against movement therein is a vertical rod 255 which is provided with a threaded lower end 256, and which extends through a lug 257 on column extension and is adjustable lengthwise therethrough by means of nuts 258. Engaging upper thrust bearing 259 and threaded in the lower end 256 of rod 255 within the casing 254 is a bevel pinion 260 with which meshes a second bevel pinion 261 fixed in the inner end of horizontal shaft 262, whose projecting outer end 263 is squared for the reception of a crank or handwheel, not shown.

It will be seen that by rotating shaft 262 by means of a crank or handwheel, the bevel pinion 261 travels up or down rod 255 to raise or lower the entire carriage 153 for the purposes mentioned. Manipulation of this mechanism is easy and not laborious, despite the weight of the carriage because the counter-balancing tension springs 171 relieve much of the weight of the carriage. It will be seen that the elevation of the carriage in this way simply lifts the end of adjusting rod 151 out of contact with push-rod 149 which is accordingly not disturbed, and the setting of the carriage reciprocating cam 157 is also not disturbed in any way. Conversely, when the carriage is again lowered, adjusting rod 151 simply again engages the upper end of push rod 149 and the carriage is restored exactly to its initial position.

Likewise, the setting of the carriage traversing cam 219 is not disturbed, as the roller 213 on the end of lever 205 simply slides up and down in its slot in block 214 as the carriage is raised and lowered. Thus, one or more tools may be removed and replaced and other changes may be made with facility and ease without disturbing the adjustment of any of the other parts of the machine.

In addition to elevating the tool carriage bodily, its vertical position with respect to the turret may be adjusted at will to change the relation between the tools and the work, such as when it is desired to begin the cut at a higher or lower point on the surface of the work. This adjustment is performed by adjusting rod 151 which raises or lowers the cross bar 150 which supports the tool carriage on the adjusting rod 151. Accordingly, by rotating adjusting rod 151 in one direction, the tool carriage may be lowered so that the grinding wheels 181 extend further into the work W, and vice versa. It will be seen that this adjustment, which should be made when the tools are out of contact with the work, does not affect the position of the tool holder traversing mechanism nor disturb the contact between the tool carriage and its reciprocating cam 157.

Summary of operation

Prior to starting the machine, the operator elevates the entire tool carriage by means of a crank placed on the squared end 263 of shaft 262 at the front of the machine (Figs. 2, 12 and 22), so that the lower ends of the tool holders 175 are accessible above the upper edge of the apron 120 of the machine. The appropriate grinding wheels 181 or other tools, of a size to accommodate the work and provide the desired grinding action, are then mounted on the lower

ends of the tool holder spindles 180. Each grinding wheel is driven by its individual motor 165 in a clockwise direction, as seen from above, i. e., opposite to the direction of rotation of the work 5 (Fig. 15).

If the surface of a rough casting, forging, or the like, is to be ground down to a fine finish or lap, the first grinding wheel or wheels of the series are coarse grinding or roughing wheels and 10 the coarseness or grinding properties of the wheels of the series are graded down to the last wheel, which may be an extremely fine grinding wheel, or even a lapping or buffing tool, depending upon the finish required. In the particular 15 machine illustrated, six tooling stations are provided requiring six grinding wheels as compared to the eight work-holding chucks, two of which are located at the loading station between each indexing movement of the turret for removal of 20 the finished work and reloading of the emptied chucks. No tool holders are provided at the loading station. Accordingly, the first tool 181 may be a coarse roughing wheel, the second tool may be a less coarse roughing tool for dressing 25 the work down to approximately the proper dimension, the third and fourth wheels may perform graded finer grinding, while the fifth and sixth wheels may provide the graded finishing grinding required for the particular work. 30 Because of the differing grinding functions required of the several grinding wheels and the gradual recession of the surface of the work being ground, the relative starting positions and feeds of the several wheels should differ appropriately in order to secure efficient, rapid and accurate grinding. Also, the coarse wheels wear down more rapidly than the fine wheels and this must be taken into consideration in order that the wheels will grind uniformly on the successive 35 pieces of work. All of these factors are taken into consideration in the present machine. For example, by adjusting the set studs 185 (Fig. 13) of the several tool holders 175, the starting position of each tool may be adjusted. Accordingly, the set stud of the first coarse tool is adjusted 40 to cut deeper into the work than the succeeding tools and the set stud of the sixth or last tool is adjusted so that it just engages the surface of the work and provides the fine finish or 45 lap.

The progressively decreasing feed of the successive tools is provided by the increased pitch of the corresponding segment of ring cam, so that the throw of the first or roughing tool is 50 greater than the throw of the second tools and so on until the sixth and last tool has a very slight throw commensurate with the fine or lapping action required thereof. The varying pitches of the segments of the cam 188 also compensate for the varying wear of the corresponding wheels which takes place in proportion to the coarseness of the wheels. 55

Having selected and attached the wheels of the proper dimensions and grades the operator 60 again lowers the tool carriage 153 by manipulating the crank on shaft 262 until the lower end of adjusting rod 151 rests upon the upper end of push rod 149, so that the unbalanced weight of the tool carriage 153 is supported by the 65 cam 157 (Fig. 9), the major proportion of the carriage weight being counterbalanced by the tension springs 171.

With the tool carriage at its lowermost position, as determined by the low track 161 of the 70 cam 157, the operator rotates adjusting rod 151,

by means of a crank placed on its squared end 152, until the tools 181 are located at their lowermost cutting position with respect to the surface of the work W, which is used as a gauge for this purpose. This adjustment of the rod 5 151 causes it to screw into or out of the cross bar 150 which supports the tool carriage 153 so that the vertical position of the carriage is adjusted. 10

The dressing tools 226 are individually adjustable by means of dials 232 so that they project 15 inwardly a very slight distance beyond the vertical plane of the surface of the work W after it is ground so as to cut and accordingly true and dress the corresponding tool during its vertical retracting movement from the work which 20 it has just finished grinding. Accordingly, although all of the tools 181 are dressed simultaneously, each tool is dressed individually according to the nature of its surface after each grinding operation. 25

After the machine has been prepared for operation, the operator starts it by throwing handle 143 to the right, as seen in Fig. 2. This rotates rod 41 so that its downwardly turned crank 42 shifts rod 40 to the left, as seen in Fig. 6, to 30 engage main drive clutch 37. The clutch 37 couples worm driven wheel 50 through ratchet 51, 52 to shaft 36, which, through worm 53 and worm wheel 54 drives cam shaft 55, which controls the operation of the several parts of the 35 machine.

Having started the machine, the operator loads the work-holding chucks as they are advanced one by one to the loading stations. In order to reach the chucks for loading the operator depresses treadle 123 to retract work holding fingers 117 from their normal position over the work-holding chucks, located at the loading station. Two chucks are in position at the loading station at a time, although advanced to this position one 40 at a time by each indexing movement of the turret. As each chuck reaches the loading station, it and the chuck preceding it are automatically opened by pins 106 aligned with the chuck spindles 84 and elevated by cam 113. Also, 45 as the chucks are brought to the loading station, their rotation is arrested by the automatic disengagement of their clutches 89, 90 by cam 105, which is engaged by the rollers 104 of the clutch release levers 102. 50

With the fingers 117 retracted from the stationary open chucks at the loading station, the operator may insert the pieces of work W therein, placing them so that the centering pins 82 of the chuck fit into the corresponding flange holes 55 of the work, as indicated in Figures 7 and 15, still assuming that the work is an automobile hub, although the chucks may be adapted to hold other pieces of work in a manner readily understood. The operator then releases treadle 123 60 and spring 125 moves fingers 117 over the pieces of work W which are engaged by the collet fingers 87 of the chucks when the latter are released by disengagement of their spindles 84 by pins 106, which are withdrawn by cam 116 immediately 65 before the next indexing movement of turret 64. 70

The dwell period of the turret is of sufficient duration to give the operator ample time to remove finished pieces of work from the chucks and replace them with new work before the turret is indexed a step and the leading chuck advanced so that its clutch release roller 104 rides off of stationary cam 105 to permit reengagement of the clutch 89, 90 by spring 99. This chuck, as well as those at the working stations, is 75 ro-

tated by ring gear 92 which is driven by bevel gear 95 of drive shaft 96. Each chuck is rotated in a counter-clockwise direction, as seen from above, which is opposite to the direction of rotation of the tools.

The turret 64 is indexed step-by-step by periodic engagement between rollers 66 on cam disc 58 with one of the spaced lugs 67 on the turret ring 68. During the period that the rollers 66 are in engagement with a lug 67, the speed of cam shaft 55, on which the cam disc 58 is mounted, is increased automatically so that the turret 64 is indexed rapidly. This speed change is provided by the variable speed mechanism which is illustrated especially in Figs. 4, 5 and 6 and is controlled by cam 59' on the cam disc 58. As the indexing movement begins, cam 59' actuates bell crank 60 to shift rod 34 to the left and engage high speed clutch 31. This clutch, through gears 30 and 35 and clutch 37 drives shaft 36 faster than it is normally driven by worm 49, and since cam shaft 55 is driven by shaft 36 through worm 53 and worm wheel 54, the cam shaft 55 is driven at greater speed and a fast indexing movement results. When cam 59' releases bell crank 60, cam 59' disengages high speed clutch 31 and the normal relatively slow drive of the cam shaft 55 results. Accordingly, the major part of the time of operation of the machine is working time, since little time is occupied in indexing and feeding the tools to and from the work. Between indexing movements of the turret, the latter is locked by pin 69 actuated by cam 74.

Assuming that the machine starts with tool carriage 153 in its uppermost position and the tool holders 175 in their inner or retracted positions, the tools 181 are located with respect to the corresponding pieces of work as is indicated by the dot-and-dash outline of one of the tools 181 in the upper left-hand corner of Fig. 14, i. e., directly above the hole in the work W but retracted out of the vertical plane of the surface to be ground.

Further rotation of tool carriage reciprocating cam 157 results in the relatively slow descent of follower 158 to the lower track 161 of the cam so that the tool carriage is lowered to its lowermost position and the tools 181 are introduced into the plane of the work and within the holes of the corresponding pieces of work, although not in contact therewith. This position of the tool is indicated by the dot-and-dash outline of the tool in the lower left-hand corner of Fig. 14.

As the tools reach the plane of the work in position for cooperation therewith, their vertical movement is arrested, except for a small reciprocation to be described, and the lateral feed of the tools in the plane of the work into cooperative relation with the surfaces to be ground takes place. This lateral feed of the tools is performed by traversing the tool holders 175 horizontally relatively to the tool carriage 153 and the turret 64. This traversing movement of the tool holders 175 is provided by rotation of ring cam 188, whose individual segments advance the corresponding actuating pins 187 to swing the tool holders 175 about their pivots 174 through an angle determined by the contour of the cam segment, so that the tools 181 are advanced in the plane of the work and engage the surface to be ground, the relative position of the tools being indicated by the full line outline in Fig. 14. This feed of the tools continues after the tools engage the work until the tools cut to the depth deter-

mined by the throws of the corresponding segments of cam 188.

The rotation of ring cam 188 to provide this feeding movement of the tools 181 in the plane of the work is performed by the radially outward throw of push rod 215 by cam 219 mounted on the upper end of cam shaft 55 (Figs. 1, 2 and 3). The push rod 215 actuates lever 205, which through locked worm 211 and worm wheel 207 rotates vertical shaft 198 having pinion 197 at its lower end, which rotates ring gear 190 in a clockwise direction as seen from above. This ring gear carries the segmental cam 188, which accordingly traverses the tool holders in the manner described.

While the tools 181 are in grinding engagement with the work W, the rippled lower track 161 of cam 157 (Fig. 9) rapidly reciprocates the tool carriage so that tools are wiped across the surface being ground to cause overlapping of the grinding rings made thereon by the abrasive particles of the tools, whereby a smoother ground surface results.

During the dwell period of tool traversing cam 219, which follows the tool feeding operation thereof, the follower 158 rises on the steep incline of cam 157 (Fig. 9) and the tool carriage is rapidly elevated, so that each tool lies in the relative position indicated by the dot-and-dash outline in the upper right-hand corner of Fig. 14, with its grinding surface in the vertical plane of the surface just ground thereby. During this upward movement of the tool carriage the surfaces of the rotating tools are raked by the dressing devices 226 as indicated in Figs. 10 and 11, so that each tool is trued and dressed individually according to its requirements, although all six of the tools are dressed simultaneously.

During the dwell period of cam 157 when the tool carriage remains in its uppermost position, cam 219 again comes into action to withdraw push rod 215 and swing lever 205 backwardly as seen in Fig. 3. This causes counterclockwise rotation of ring cam 188 and the resultant retraction of tool holders 175 by their springs 194, so that the tools are traversed laterally inwardly, as seen in Fig. 14. Just prior to the end of the retracting movement of lever 205, the free end of bell crank lever 243 engages and is actuated by abutment 245, and, by means of link 241, actuates pawl 237 which rotates ratchet wheel 235, worm 211, worm wheel 207, shaft 198, attached pinion 197, and ring gear 190 through a small angle. It is noted that this resulting small movement of cam 188 is superimposed upon and is opposite to the major movement of the cam 188 produced by the rearward movement of lever 205 by cam 219. This reduces the net retractive movement of the tools 181 an amount equal to the reduction in radius of the tools caused by the wearing and dressing thereof, so that during the subsequent feeding movement of the tools to the work they are advanced to the same relative position with respect to the next pieces of work as they occupied with respect to the preceding pieces of work during the tooling operation. In other words, the reduction in radius of the tool is automatically compensated for, even to the extent of compensating for the varying degree of wear of the several tools, since the corresponding segments of cam 188 have varying pitches. For example, the pitch of the cam segment of the first or roughing wheel is greater than that of the remaining segments because of the deeper cutting required of it. The roughing wheels also wear

faster than the finer wheels, so that a greater compensation for wear is required. This greater compensation naturally results because of the increased pitch of the cam segment of the roughing wheel. Accordingly the wear of each wheel is compensated for to a degree commensurate to the wear thereof.

As the tools gradually wear down to the core or to a point where they are no longer effective, the compensating mechanism is disabled by cam 248 on worm wheel 207 of the compensating mechanism (Figs. 17, 18 and 19). This cam is stepped around to the point where a tool wears down and releases latch 250 which is projected into the path of pawl carrier 236 to prevent further compensating movement thereof. Since some wheels wear down sooner than others, only those wheels need to be replaced at a time. The dial on shaft 198 at the loading station (Fig. 2) indicates the condition or position of the compensating mechanism at all times.

During the retracting and compensating movements of the tools in the horizontal plane above the plane of the work, the indexing movement of the turret 64 takes place, whereby each piece of work is advanced a step in alignment with the tool which is to perform the next tooling operation, with the exception of the piece of work which was acted upon by the sixth or finishing tool and this piece of work is advanced to the unloading station for removal and replacement by a new piece of work. As aforementioned this indexing movement is rapid, being provided by the high speed gearing of the main driving mechanism.

If the operator fails to depress treadle 123 preparatory to removing the finished work, the cam 134 (Figs. 1 and 2) actuates levers 129 and 127 and detent 136 engages abutment 138 to drop hook 142 into engagement with pin 143' of control handle 143. The continued movement of lever 127 by cam 134 causes hook 142 to pull handle 143 to the left, as seen in Fig. 2, so as to disengage main drive clutch 37 (Fig. 6) and stop the machine. This prevents regrinding of the finished piece of work. However, if the operator depresses treadle 123 at the proper time, lever 127 and detent 136 are lowered, as illustrated in Fig. 21, so that upon movement of lever 127 to the right by cam 134, detent clears abutment 138, while detent 137 engages abutment 139 to lift hook 142 clear of pin 143', so that the handle 143 is not actuated. This safety arrangement accordingly "feels" whether or not the operator has acted to remove the finished work, and if he has not, the mechanism responds by stopping the machine.

This safety arrangement also has another safety function. If the operator is in the act of replacing work in an open chuck at the loading station, holding treadle 123 depressed at the time in order to hold fingers 117 out of the way, but is unable to complete the loading operation before the chuck closes, the latch 141 will also engage pin 143', so that the subsequent feeler action of cam 134 will stop the machine before the partially loaded chuck is carried to a grinding station with consequent injury to the work and possible injury to the associated machine parts.

The foregoing describes the single indexing movement of the turret when each successive tool engages each successive piece of work. Under certain conditions it is desirable to double index, i. e., present the work to alternate tools for per-

forming different grinding operations, such as inside grinding at alternate stations and outside grinding at the remaining stations, grinding of different aligned surfaces either inside or outside of the work, grinding alternate pieces of work in the reversed position, and the like. Also if a small amount of stock is to be removed the double chucking arrangement would increase production. In any case, two pieces of work are loaded at a time at the loading station, and there would be three grinding stations for each piece instead of six, as in the case of the single indexing movement described. As aforementioned, the machine may be converted quickly and simply into double indexing by substituting the four-roller cam disc illustrated in Figure 4A for the two-roller disc 58 illustrated in Figure 4, the four rollers 66' securing the double angle movement and cam 59' holding locking pin 69 out of engagement with alternate notches 70 to permit the double index.

It will be seen that in the machine of the present invention the individual pieces of work are treated at each station to the particular cutting action which is necessary to secure the desired result most rapidly, efficiently and economically. This involves variable feeding of the several tools, depending upon their abrasive properties, the nature of the cut required of them and the condition of the surface of the work being tooled. Each of these factors is accommodated by the independent feed and adjustability of the individual tools, which are not dependent upon the movements of massive machine parts and accordingly can be as delicate and accurate as the nature of the work requires.

Among the numerous novel features of the machine, especial importance is attached to the mounting and correlation of the grinding wheels and the dressing tools by which the wheels are dressed after each grinding operation. These dressing tools are mounted with their cutting points practically in alignment with the ground surfaces of the pieces of work being operated upon. As a result, the movement of the grinding wheels in a straight line out of coaction with the pieces of work just ground thereby, carries their grinding surfaces into coaction with and past the cutting surfaces of the dressing tools, so that extreme accuracy in the dressing of the tools is attainable and such extreme accuracy is essential to the successful operation of a machine for such uses as those for which the present machine is particularly adapted.

Also, while the grinding wheels are all mounted upon the same tool carriage and are moved axially thereby, they are all capable of different amounts of movement in a substantially radial direction and the movement of each is independent of the movement of all the other tools. Although the several grinding tools are moved in a substantially radial direction each independently of all the others, the machine of this invention employs a single compensating means governing all of them to compensate for the wear on the grinders incident to the grinding operation and for the dressing of the grinding tools. The use of a single compensating means for all of the tools rather than individual compensating means for each of the several grinding tools is made possible because of the individual actuating means for positioning the several grinding tools, i. e., the individual segments of the ring cam 188. It is by reason of the use of these several individual actuating means for positioning the tools each

independently of all the others that unnecessary excess wear of some of the tools is avoided, the maximum service of each of the grinders is attained, and the substitution of a single new 5 grinder at any time is possible.

The use of individual motors for the several tools permits adjustment of the speed of rotation of the tools commensurate with the work required of them, and this adjustment is made either by 10 regulating the speed of the motors by well known means or by employing driving pulleys of the proper diameters.

Although the machine has been illustrated and described as performing inside grinding, it will 15 perform outside grinding with equal facility and the various movements of the machine may be employed for performing tooling operations other than grinding.

I claim:

20 1. In a machine of the class described, the combination of a work holding member having a plurality of work holders arranged in circular series, a tool holding member having a plurality of tool holders arranged in circular series, means for 25 moving the members relatively axially to place the tools and the work into position for cooperative relation, and means for simultaneously moving the tool holders laterally with respect to said tool holding member and independently of the movement 30 of the members to engage the tools with the work.

2. In a machine of the class described, the combination of a work holding member having a plurality of work holders arranged in circular series, a tool holding member having a plurality of tool holders arranged in circular series, means for intermittently moving the members relatively angularly to place the tools and the work successively into position for cooperative relation, and 35 means for simultaneously moving the tool holders laterally with respect to said tool holding member and independently of the movement of the members to engage the tools with the work.

3. In a machine of the class described, the combination of a work holding member having a plurality of work holders arranged in circular series, a tool holding member having a plurality of tool holders arranged in circular series, means for intermittently moving the members relatively 40 angularly to successively place the work and tools in substantial alignment, means for moving said members relatively axially to place the tools and the work into position for cooperative relation, and means for simultaneously moving the tool holders laterally with respect to said tool holding member and independently of the movement of the members to engage the tools with the work.

4. In a machine of the class described, the combination of a work holding member having a plurality of work holders arranged in circular series, a tool holding member having a plurality of tool holders arranged in circular series, means for moving the members relatively axially to place the tools and work into position for working 45 engagement, means for simultaneously moving the tool holders laterally with respect to said tool holding member and independently of the movement of the members to engage the tools with the work, and means for relatively reciprocating the tools and work while in engagement independently of the movement of the tools and work into and out of engagement.

5. In a machine of the class described, the combination of a work holding member having a plurality of work holders arranged in circular se-

ries, a tool holding member having a plurality of tool holders arranged in circular series, means for simultaneously moving the tool holders laterally with respect to said tool holding member and independently of the movement of the members to engage the tools with the work, and means for relatively reciprocating the members while the work and tools are in engagement independently of the movement of the tools and work into and out of engagement.

6. In a machine of the class described, the combination of a work holding member having a plurality of work holders arranged in circular series, a tool holding member having a plurality of tool holders arranged in circular series, means for moving said members relatively to place the tools and the work into position for cooperative relation, means for simultaneously moving the tool holders relatively to the work holders independently of the said relative movement of the members, and means responsive to the movement of the tool holders for advancing the latter after each operation to compensate for the wear of the tools.

7. In a machine of the class described, the combination of a work holding member having a plurality of work holders arranged in circular series, a tool holding member having a plurality of tool holders arranged in circular series, means for moving the tool holders relative to the work holders for feeding the tools into engagement with the work, means for relatively moving the tool holders and the work holders axially out of engagement, a relatively stationary dressing device in the path of the said relative axial movement of each tool for dressing the surface thereof, and mechanism responsive to the said feeding movement of the tool holders for adjusting the first means to compensate for the dressing of the tools.

8. In a machine of the class described, the combination of a work holding member having a plurality of work holders arranged in circular series, a tool holding member having a plurality of tool holders arranged in circular series, means for moving the members relatively axially to place the tools and work into position for cooperative relation, means for traversing the tool holders laterally with respect to the members and independently of movement of said members to engage the tools and the work, and means responsive to the traversing movement of the tool holders for simultaneously varying the relation between the tools and the work to compensate for the wear of the tools.

9. In a machine of the class described, the combination of a work holding member having a plurality of work holders arranged in circular series, a tool holding member having a plurality of tool holders arranged in circular series, means for relatively moving the members axially to place the tools and work into and out of position for cooperative relation, means for relatively moving the members step-by-step to present the tools and work successively for the said cooperative relation, and means alternating with the relative axial movements of the members for advancing and retracting the tool holders substantially radially with respect to the members and independently of the movement thereof, whereby the tools describe a substantially rectangular path with respect to the corresponding pieces of work.

10. In a machine of the class described, the combination of a work holding member having a

- plurality of work holders arranged in circular series, a tool holding member having a plurality of tool holders arranged in circular series, means for relatively moving the tools and work into cooperative relation, means for relatively moving the members step-by-step to place the successive tools and work in position for the said cooperative relation, means timed with the relative step-by-step movement of the members for successively 5 opening the work holders at an unloading station, means preventing removal of the work from the work holders, manual means at the unloading station for disabling said last named means, and means responsive to failure of operation of said 10 manual means for disabling at least the step-by-step means to prevent finished work from being carried past the unloading station.
11. In a machine of the class described, the combination of a work holding member having a plurality of work holders arranged in circular series, a tool holding member having a plurality of tool holders arranged in circular series, common means for simultaneously feeding the several 15 tools into cooperative relation with the corresponding pieces of work, and variable devices in the feeding means for adjusting the position of at least part of the tools relatively to the corresponding pieces of work and the other tools.
12. In a machine of the class described, the combination of a work holding member having a plurality of work holders arranged in circular series, a tool holding member having a plurality of tool holders arranged in circular series, common means for simultaneously feeding the several 20 tools into cooperative relation with the corresponding pieces of work, and devices in the feeding means for varying the feed of the individual tools relatively to the corresponding pieces of work and the other tools.
13. In a machine of the class described, the combination of a work holding member having a plurality of work holders arranged in circular series, a tool holding member having a plurality of tool holders arranged in circular series, means for feeding the several tools into cooperative relation with the corresponding pieces of work, means for relatively moving the members step-by-step to present the tools and work successively to each other, means for independently adjusting 25 the tools with respect to each other to provide different tool action on the successive pieces of work, and common means for feeding the tools to and from the work.
14. In a machine of the class described, the combination of a work-holding member having a plurality of work holders, a tool holding member having a plurality of tool holders corresponding to at least part of the work holders, means for simultaneously relatively moving the work 30 holders and tool holders to place the tools and work into and out of cooperative relation, means for relatively moving the members step-by-step to place the several tools and pieces of work successively in position for the said cooperative relation, and means responsive to the said relative movement of the work holders and the tool holders for varying the relationship between each tool and each successive piece of work relatively to the other tools and prior to the said cooperative 35 relation between them.
15. In a machine of the class described, the combination of a turret having a plurality of work holders arranged in circular series, a tool carriage aligned axially with the turret, a plurality 40 of tool holders mounted on the tool carriage in circular series and traversible substantially radially with respect thereto, means for intermittently indexing the turret to substantially align successive tools and pieces of work, means for reciprocating the tool carriage for advancing and withdrawing the tools into and out of the plane of the work, and means for traversing the tool holder to feed the tools to the work when in the plane of the latter and for retracting the tool holders laterally relatively to the tool carriage when withdrawn from the plane of the work by the tool carriage.
16. In a machine of the class described, the combination of a turret having a plurality of work holders arranged in circular series, a tool carriage aligned axially with the turret, a plurality of tool holders mounted on the tool carriage in circular series and traversible substantially radially with respect thereto, means for intermittently indexing the turret to substantially align successive tools and pieces of work, means for reciprocating the tool carriage for advancing and withdrawing the tools into and out of the plane of the work, and a cam for traversing the tool holders inwardly and outwardly in a substantially radial direction relatively to the tool carriage for alternately feeding the tools into engagement with the work when in the plane thereof and retracting the tools when out of the plane of the work.
17. In a machine of the class described, the combination of a turret having a plurality of work holders arranged in circular series, a tool carriage aligned axially with the turret, a plurality of tool holders mounted on the tool carriage in circular series and traversible substantially radially with respect thereto, means for intermittently indexing the turret to substantially align successive tools and pieces of work, means for reciprocating the tool carriage for advancing and withdrawing the tools into and out of the plane of the work, a cam for traversing the tool holders inwardly and outwardly in a substantially radial direction relatively to the tool carriage for alternately feeding the tools into engagement with the work when in the plane thereof and retracting the tools when out of the plane of the work, and means for adjusting each tool holder relatively to the cam.
18. In a machine of the class described, the combination of a turret having a plurality of work holders arranged in circular series, a tool carriage aligned axially with the turret, a plurality of tool holders mounted on the tool carriage in circular series and traversible substantially radially with respect thereto, means for intermittently indexing the turret to substantially align successive tools and pieces of work, means for reciprocating the tool carriage for advancing and withdrawing the tools into and out of the plane of the work, a cam for traversing the tool holders inwardly and outwardly in a substantially radial direction relatively to the tool carriage for alternately feeding the tools into engagement with the work when in the plane thereof and retracting the tools when out of the plane of the work, and means responsive to each traversing movement of the tool holders in one direction for adjusting the cam relatively to the tool holders to compensate for the wear of the tools.
19. In a machine of the class described, the combination of a turret having a plurality of work holders arranged in circular series, a tool carriage aligned axially with the turret, a plurality of tool holders mounted on the tool carriage in circular series and traversible substantially

- radially with respect thereto, means for intermittently indexing the turret to substantially align successive tools and pieces of work, means for reciprocating the tool carriage for advancing and withdrawing the tools into and out of the plane of the work, and an oscillating cam having a segment for each tool holder of a contour appropriate for providing the requisite movement of the corresponding tool. 5
20. In a machine of the class described, the combination of a turret having a plurality of work holders arranged in circular series, a tool carriage aligned axially with the turret, a plurality of tool holders mounted on the tool carriage 10 in circular series and traversible substantially radially with respect thereto, means for intermittently indexing the turret to substantially align successive tools and pieces of work, means for reciprocating the tool carriage for advancing 15 and withdrawing the tools into and out of the plane of the work, means for traversing the tool holders relatively to the tool carriage to feed the tools into cooperative relation with the corresponding pieces of work, means responsive to the traversing movement of the tool holders for advancing them relatively to the work to compensate for wear of the tools, and stop mechanism for disabling the compensating means upon wearing down of at least one of the tools. 25
21. In a machine of the class described, the combination of a turret having a plurality of work holders arranged in circular series, a tool carriage aligned axially with the turret, a plurality of tool holders mounted on the tool carriage 30 in circular series and traversible substantially radially with respect thereto, means for intermittently indexing the turret to substantially align successive tools and pieces of work, means for reciprocating the tool carriage for advancing 35 and withdrawing the tools into and out of the plane of the work, means for rotating the work holders, a normally engaged clutch in the rotating means of each work holder, and means responsive to the indexing movements of the turret for disengaging the clutch of certain of the work holders to stop the rotation thereof during the corresponding indexing movement of the 40 turret.
22. In a machine of the class described, the combination of a turret having a plurality of work holders arranged in circular series, a tool carriage aligned axially of the turret, a plurality of tool holders pivoted on the tool carriage in circular series and swingable about their pivots 45 relatively to the tool carriage, an individual motor for each tool holder, a cam for swinging the tool holders to feed the tools into and out of cooperative relation with the work, means for reciprocating the tool carriage axially of the turret to advance and withdraw the tools into and out of the plane of the work and means for intermittently indexing the turret when the tools are withdrawn from the plane of the work for presenting successive pieces of work to the tools. 50
23. In a machine of the class described, the combination of a turret having a plurality of work holders arranged in circular series, a tool carriage aligned axially with the turret, a plurality of tool holders mounted on the tool carriage in circular 55 series and traversible substantially radially with respect thereto, means for intermittently indexing the turret to substantially align successive tools and pieces of work, means for reciprocating the tool carriage for advancing and withdrawing the tools into and out of the plane of the work, 60 and means for withdrawing the tool carriage independently of the reciprocating means thereof and without disturbing the latter. 65
24. In a machine of the class described, the combination of a turret having a plurality of work holders arranged in circular series, a tool carriage aligned axially with the turret, a plurality of tool holders mounted on the tool carriage in circular series and traversible substantially radially with respect thereto, means for intermittently indexing the turret to substantially align successive tools and pieces of work, means for reciprocating the tool carriage for advancing and withdrawing the tools into and out of the plane of the work, and means for adjusting the elevation of the tool carriage independently of the reciprocating means to change the axial relationship between the tool carriage and the turret. 70
25. In a grinding machine, the combination of a turret rotatable step-by-step, a plurality of rotatable work-holders mounted in circular series upon the turret, a tool carriage mounted in axial alignment with the turret and movable axially with respect thereto, a plurality of tool holders mounted on the tool carriage in circular series, means for rotating the tool holders, grinding tools mounted upon the tool holders, means for simultaneously moving said grinding tools laterally relative to the tool carriage independently of the movement of the carriage to engage the tools with the work, and a plurality of dressing tools each corresponding to one of the grinding tools and each mounted with its cutting edge in alignment with the surface ground and in position to be engaged by the grinding surface of the grinding tool as the grinding tool is moved out of coaction with the work being operated upon by the axial movement of the tool carriage relatively to the turret. 75
26. In a grinding machine, the combination of a turret, a plurality of work holders arranged in circular series thereon, means for rotating the work holders, means for indexing the turret, a tool carriage mounted for movement axially with respect to the turret, a plurality of tool holders mounted on the tool carriage, means for rotating the tool holders, grinding tools mounted on the tool holders, means for moving the grinding tool holders substantially radially in alternation with axial movements of the tool carriage relatively to the turret, whereby each of the grinding tools is caused to traverse a substantially rectangular path, a plurality of dressing tools each corresponding to one of the grinding tools and each mounted with its cutting edge in alignment with the aligned surfaces of the grinding tool and the surface of the work ground thereby in position to be engaged by the corresponding grinding tool during the axial movement of the tool carriage. 80
27. In a grinding machine, the combination of a turret, a plurality of work holders arranged in circular series thereon, means for rotating the work holders, means for indexing the turret, a tool carriage mounted for movement axially with respect to the turret, a plurality of tool holders mounted on the tool carriage, means for rotating the tool holders, grinding tools mounted on the tool holders, means for moving the grinding tool holders substantially radially relatively to the tool carriage in alternation with axial movements of the tool carriage relatively to the turret, whereby each of the grinding tools is caused to traverse a substantially rectangular path, the said means for effecting movement of the tool 85 carriage. 90

holders in the radial direction being arranged to move the several tool holders varying amounts.

28. In a grinding machine, the combination of a turret, a plurality of work holders arranged in circular series thereon, means for rotating the work holders, means for indexing the turret, a tool carriage mounted for movement axially with respect to the turret, a plurality of tool holders mounted on the tool carriage, means for rotating the tool holders, grinding tools mounted on the tool holders, means for moving the grinding tool holders substantially radially relatively to the tool carriage in alternation with axial movements of the tool carriage relatively to the turret, where-
10 by each of the grinding tools is caused to traverse a substantially rectangular path, and a compensating means for varying the amplitude of the movement of the tool holders in the said radial direction to compensate for variation in the size
15 of the grinding tools as the grinding operation proceeds.

29. In a grinding machine, the combination of a turret having a plurality of rotatable work holders in circular series thereon, means for indexing the turret, a tool carriage aligned axially with the carrier, a plurality of rotatable tool holders mounted on the tool carriage in circular series, grinding tools upon the tool holders, means for moving the tool carriage in the axial direction relatively to the turret, and means for moving the tool holders and their corresponding tools in the radial direction relatively to the tool carriage each independently of the others and alternately with the axial movements of the tool carriage to cause the several tools to traverse a substantially rectangular path, the radial movements of the tool holders in one direction carrying the grinding surfaces of the tools into coaction with the surfaces of the work to be ground mounted in the work holders and the axial movements of the tool carriage carrying the tools into and out of the plane of the surfaces to be ground.

30. In a machine of the class described, the combination of a turret having a plurality of work holders arranged in circular series, a tool carriage aligned axially of the turret, a plurality of tool holders pivoted on the tool carriage in circular series and swingable about their pivots relatively to the tool carriage, an individual motor for each tool holder, flexible driving connections between the tool of each tool holder and the corresponding motor permitting the swinging movement of the tool holder, and means for swinging the tool holders to bring the corresponding tools into and out of cooperative relation with the work.

31. In a machine of the class described, the combination of a turret having a plurality of work holders arranged in circular series, a tool carriage aligned axially of the turret, a plurality of tool holders pivoted on the tool carriage in circular series and swingable about their pivots relatively to the tool carriage, an individual motor for each tool holder, said motor and corresponding tool holder being mounted eccentrically with respect to each other, and means for swinging the tool holders to bring the corresponding tools into cooperative relation with the work.

32. In a machine of the class described, the combination of a rotatable turret having a plurality of work holders arranged in circular series, an axis therefor, a tool carriage axially aligned with the turret and having a plurality of tool holders arranged in circular series for operating
75 on successive pieces of work mounted in the tur-

ret work holders, and means adjacent the finishing stations for the work for urging the turret against its axis to take up play between the turret and its axis at the finishing stations.

33. In a machine of the class described, the combination of a work holder, a movable tool holder having a tool for cooperating with the work in the work holder, a rigid support, a movable cam bearing on the support and interposed between the support and the tool holder for moving the latter to bring the tool into engagement with the work, and means independent of the support for moving the cam along the support to actuate the tool holder.

34. In a grinding machine, the combination of a work holding member having a plurality of work holders arranged in circular series, a tool holding member having a plurality of tool holders arranged in circular series, means for feeding the several tools variable distances into cooperative relation with the corresponding pieces of work, and means for compensating for the wear of each tool in proportion to the amount of feed thereof.

35. In a grinding machine, the combination of a turret having a plurality of work holders arranged in circular series, a tool carriage having a plurality of tool holders arranged in circular series, means for feeding the several tools variable distances into cooperative relation with the corresponding pieces of work, and means responsive to the movements of the tools for changing the positions thereof to compensate for the wear of each tool in proportion to the amount of feed thereof.

36. In a grinding machine, the combination of a turret having a plurality of work holders arranged in circular series, a tool carrier having a plurality of tool holders arranged in circular series, means for intermittently moving the turret to carry the work holders progressively from one tool to another, and means for simultaneously feeding the individual tools varying amounts in relation to one another toward the work.

37. In a grinding machine, the combination of a turret having a plurality of work holders arranged in circular series, a tool carrier having a plurality of tool holders arranged in circular series, means for intermittently moving the turret to carry the work holders progressively from one tool to another, means for feeding the individual tools varying amounts in relation to one another toward the work, means for compensating for the wear of each tool in proportion to the amount of feed thereof, and means for adjusting the position of each tool in relation to the work independently of the other tools.

38. In a grinding machine, the combination of a turret having a plurality of work holders arranged in circular series, a tool carrier having a plurality of tool holders arranged in circular series, grinding tools mounted on the tool holders, means for intermittently moving the turret angularly to successively place the work and tools in substantial alignment, means for feeding the several tools variable distances into cooperative relation with the corresponding pieces of work, means for adjusting the position of each tool in relation to the work independently to the other tools, means for moving the tool holders substantially axially with respect to the work holders to disengage the tools from the work, and a plurality of dressing devices each corresponding to one of the grinding tools and mounted with its working edge in alignment with the finished sur-
65
70
75

face of the work and in position to be engaged by the grinding surface of the tool during the axial movement of the tool holder to disengage the tool from the work.

- 5 39. A machine of the class described comprising a bed, a turret rotatable thereon, a plurality of work-holders radially arranged on said turret, a plurality of tools on said bed, said tools being arranged for simultaneous alignment with certain of said work-holders, means for traversing said tools across the work, and means for feeding said tools gradually against the work during the operative engagement of the tools therewith, said feeding means including a separate cam and cam follower for each tool, and common driving means for said cams.
- 10 40. A machine of the class described comprising a bed, a turret rotatable thereon about a vertical axis, a plurality of rotatable work-holders radially arranged on said turret, a plurality of tools on said bed, said tools being arranged for simultaneous alignment with certain of said work-holders, common driving means for said work-holders, means for simultaneously traversing said tools axially with reference to the work, means for laterally feeding the several tools at independent rates and for independent distances, and common driving means for the several feeding means.

41. A machine of the class described, comprising a support, a plurality of work-holders on said support, a plurality of tools each of which is approximately aligned with one of said work-holders, means for simultaneously traversing said tools toward and from their respective work-holders to pass across the face of the work, and means for feeding said tools laterally against the work, said feeding means including a separate cam and cam follower for each tool, and common driving means for said cams. 5

42. In a machine of the class described, the combination of a turret having a plurality of work holders arranged in circular series, a tool holding member having a plurality of tool holders 15 arranged in circular series, means for intermittently indexing the turret to substantially align successive tools and pieces of work, means for moving the tool holders into and out of cooperative rotation with the corresponding pieces of 20 work, means for rotating the work holders, a normally engaged clutch in the rotating means of each work holder, an arm operatively connected with each clutch and carried by its corresponding work holder, and a stationary cam adapted upon 25 each index of said turret to engage the arm of a work holder to release the clutch thereof.

ARTHUR J. LEWIS.
